FRAME FOR OVERHEAD CAR WASH UNIT

Daniel C. Hanna, 1133 SW. Rivington Drive,
Portland, Oreg. 97201

Filed June 14, 1974, Ser. No. 479,308

Term of patent 14 years

Int. Cl. D15—05

U.S. Cl. D49—12

FIG. 1 is a top plan view of a frame for overhead car wash unit embodying my new design;

FIG. 2 is a side elevation view thereof;

FIG. 3 is a bottom plan view thereof;

FIG. 4 is a rear elevation view thereof; and

FIG. 5 is a front elevation view thereof.

I claim:

The ornamental design for a frame for overhead car wash unit, as shown.
